United States Patent Office

Des. 186,257
Patented Sept. 29, 1959

186,257

HAIRPIN

Nathan L. Solomon, Englewood, N.J.

Application April 6, 1959, Serial No. 55,352

Term of patent 14 years

(Cl. D86—10)

Fig. 1.

Fig. 2.

Fig. 3.

Fig. 4.

Fig. 5.

Figure 1 is a front perspective view of a hairpin showing my new design;

Figure 2 is a front elevational view, the opposite side being substantially a mirror image thereof;

Figure 3 is a side elevational view, the opposite side being substantially a mirror image thereof;

Figure 4 is a top plan view thereof; and

Figure 5 is a bottom plan view thereof.

I claim:

The ornamental design for a hairpin, as shown and described.
